UNITED STATES PATENT OFFICE.

JOHN SCHILLING AND ABRAM ALBERT MASSAR, OF POMEROY, OHIO.

DOOR-LOCK.

SPECIFICATION forming part of Letters Patent No. 289,031, dated November 27, 1883.

Application filed September 19, 1883. (Model.)

To all whom it may concern:

Be it known that we, JOHN SCHILLING and ABRAM ALBERT MASSAR, citizens of the United States, and residents of Pomeroy, in 5 the county of Meigs and State of Ohio, have invented certain new and useful Improvements in Locks; and we do hereby declare that the following is a full, clear, and exact description of the invention, which will enable others skilled in the art to which it appertains to make and use the same, reference being had to the accompanying drawings, which form a part of this specification, and in which—

Figure 1 is a side view of the entire lock 15 mechanism with one side of the lock-casing removed. Fig. 2 is a horizontal section of the same on line *x x*, Fig. 1; and Fig. 3 is a vertical sectional detail view on line *y y*, Fig. 1.

Similar letters of reference indicate corresponding parts in all the figures.

Our invention has relation to that class of locks in which the lock-bolt forms a frame, inside of which a slide operated by the key slides, serving to lock the lock-bolt by bearing 25 against the inside of the forward end of the frame; and it consists in the improved construction and combination of parts of the same, as hereinafter more fully described and claimed.

30 In locks of this class the slide which holds the lock-bolt locked has heretofore been sliding vertically, bearing only with one corner against a shoulder in the outer end of the frame, by which construction it has been possible to force the lock-bolt back, the point of resistance being comparatively small; and to avoid this we construct a lock in which the slide operated by the key bears with its entire outer end against the outer end of the frame 35 when locked, the slide sliding horizontally, thus holding the lock-bolt perfectly secure in place.

In the accompanying drawings, the letter A indicates the casing, which is of the usual 45 construction, and may be made to serve for a mortise or face lock, as desired.

B is the bolt, which is shown in the drawings as having a beveled face for use in a face-lock, and the inner portion of which forms an open 50 frame, C, having a half-round recess, D, in its

inner end and a rectangular recess, E, in its outer end to the rear of the beveled outer end of the bolt.

A sleeve, F, having a central perforation, G, for the reception of the lock-spindle, and 55 having two diametrically-opposite arms or lugs, H, upon its sides, turns in perforations I in the casing and in the half-round recess in the bolt, and the lugs bear, when the bolt is forced out, against one of two pairs of shoulders, J, upon the rear end of the bolt, one pair of shoulders being on each side of the bolt.

A spring, K, bears with one end against the inner side of the lock-casing, fitting into a 65 notch in the same, and bears with the other end against the rear end of the bolt, fitting in a notch in the same, forcing the bolt out, while by turning the lock-spindle and sleeve one of the arms upon the latter will press against one 70 of the shoulders upon the bolt, forcing it back.

In the rear side of the casing is pivoted a lever or catch, L, having one end projecting outside the casing, while its other end will bear against the rear end of the bolt when 75 tilted downward.

M is the slide, the outer or forward end, N, of which is rectangular, fitting into the rectangular recess in the bolt, while its lower edge is cut out at O, to correspond to the shape of 80—the key, which is inserted through the key-hole P, and the lower edge is cut out to the rear of the notch O for the key, to form two half-round notches, Q, having a rounded bulge, R, between them, which notches fit 85 over a pin, S, fastened in the lock-casing, the foremost notch fitting over the pin when the slide is pushed back, releasing the bolt, and the rearmost notch fitting over the pin when the slide is pushed forward, locking the bolt. 90 A flat spring, T, fits with one end into a notch in the upper edge of the slide, and bears with its upper side against a pin, U, fastened in the casing above the slide, and serves to force the latter down against the key and force the 95 notches to catch over the lower pin. In this manner it will be seen that the lock may be used as a common latch by unlocking the slide, while by locking the slide it will prevent the bolt from being drawn back. It will 100

also be seen that the lock may be used as a right or left handed lock, as desired, by turning the bolt, bringing the beveled face to either side, there being two pairs of shoulders 5 upon the rear end for the lugs upon the sleeve to act upon.

We are aware that locks have been made with the inner portion of the lock-bolt forming a frame, against the outer end of which a 10 slide operated by the key may bear when locked, as shown in Patent No. 217,693, granted to E. A. Kimball July 22, 1879, and we do not wish to claim such construction, broadly; but

15 What we claim, and desire to secure by Letters Patent of the United States, is—

The combination of a lock-bolt having means for operating it and forming a frame at its inner portion, having a rectangular recess at its outer end, with a key-operated horizontal slide fitting with its outer end into said recess when locked, as and for the purpose shown and set forth.

In testimony that we claim the foregoing as our own we have hereunto affixed our signatures in presence of two witnesses.

JOHN SCHILLING.
ABRAM ALBERT MASSAR.
